W.M. Roach

Attorney

UNITED STATES PATENT OFFICE.

FRANK J. JERVEY, OF CHARLESTON, SOUTH CAROLINA.

COMBINATION MOUNT FOR MACHINE GUNS.

Application filed May 18, 1927. Serial No. 192,421.

(GRANTED UNDER THE ACT OF MARCH 3, 1883, AS AMENDED APRIL 30, 1928; 370 O. G. 757.)

The invention described herein may be manufactured and used by or for the Government for governmental purposes without the payment to me of any royalty thereon.

5 The subject of this invention is a combination mount for machine guns.

In employing machine guns against ground targets a low stable mount is required in order to afford protection to both 10 the gun crew and advancing friendly troops while in directing the guns against aerial targets a high mount is of prime consideration to facilitate aiming and manipulation of the gun.

15 The introduction of the machine gun as an anti-aircraft weapon imposes the necessity of providing infantry units with a mount capable of directing the gun for high angle as well as low angle fire.

20 The purpose of the present invention is to reorganize the standard low mount by equipping it with an adaptor to enable it to be used for this dual assignment.

An adaptor to meet the requirements of 25 service must fulfill the following conditions:

It must be simple, compact, light and an integral part of the mount, not interfering with ground fire, permitting a gun elevation of at least 80°, capable of being conveniently moved in adjustment in a minimum time without disturbing the ammunition belt and without requiring handling of the hot gun by the personnel and having sufficient clearance to permit the efficient

30 direction of fire. In addition to these requirements the adaptor must possess the characteristics of rigidity, stability, and convenience in folding to the mount for transportation.

40 With the foregoing and other objects in view, my invention resides in the novel arrangement and combination of parts and in the details of construction hereinafter described and claimed, it being understood that changes in the precise embodiment of the invention herein disclosed may be made within the scope of what is claimed without departing from the spirit of the invention.

45 A practical embodiment of the invention is illustrated in the accompanying drawing, wherein:

Fig. 1 is a view in side elevation of a

mount showing the adaptor arranged for low angle firing;

55 Fig. 2 is a similar view with the adaptor in position for anti-aircraft firing;

Fig. 3 is a detail sectional view on the line 3—3 of Fig. 1;

60 Fig. 4 is a plan view of the adaptor;

Figs. 5 and 6 are detail views, respectively, in plan and side elevation of the pocket members;

65 Fig. 7 is a detail view showing an altered method of engaging the adaptor.

Referring to the drawings by numerals of reference:

The elements which form the standard mount for firing a gun at low angles against ground targets comprise a tripod 5 receiving a pintle 6 on which a cradle 7 is mounted by means of the trunnion pin 8. A bolt 9 in the pintle passes through slots 10 in the cradle plates and carries a clamping handle 11 which binds the cradle in position of angular adjustment. At the free end of the cradle is an elevating mechanism 12 having a provision 13 for attaching the rear end of the gun by means of the pin 14.

70 In modifying the cradle to carry an adaptor which will permit high angle firing against aerial targets the apertures which are provided adjacent the pintle in the combined cradle plates and the adaptor plates

75 15 for the forward attachment of a gun are converted into recesses 16 which form bearings substantially in line with the rear gun attachment 14 and trunnions 8 for receiving the forward gun attaching pin 17. This pin passes through apertures in the 80 rear or upper end of the adaptor 18. The adaptor comprises spaced plates having slots

85 19 for receiving the trunnion pin 8 externally of the cradle 7 and a cross piece 20 which is arranged to bear against the forward edges of the cradle for the purpose

90 not only of supporting the adaptor but also of enlarging the area of application of the thrust transmitted to the cradle and distributing it to include points below and forward of the cradle trunnion. This measure will increase the stability of the cradle as an independent unit and also increase the 95 stability of the entire mount. The cross piece 20 is extended beyond the cradle for

100 105 the purpose of strength and so that it may

be guided thereby in adjusting the adaptor to its upright position for aerial firing.

With the rear gun attaching pin 14 removed the adaptor carrying the gun by means of the forward pin 17 may be elevated by reason of the sliding connection established by the trunnion 8 and slots 18. When elevated sufficiently to clear all obstructing members it is swung to a vertical position and then allowed to drop until its lower extremities are engaged with a fixed member. This engagement may be accomplished by means of pockets 21 secured to the cradle plates as shown in Figs. 1 to 6 or the clamping bolt 9 may be utilized to receive the bifurcated end 22 of the adaptor as shown in Fig. 7 and again indicated in dotted lines in Fig. 3.

In order to provide for clamping the adaptor without interfering with the freedom of movement of the cradle a pair of abutting bushings 23 are pressed on the trunnion 8 and serve as an anvil when the clamping handle 24 is turned on the trunnion.

In arranging the mount for carrying, the adaptor folds over the cradle as indicated in dotted lines in Fig. 2.

From the foregoing it will be evident that the operation of mounting and dismounting the gun will be conducted in the usual manner, that only one pin need be removed to prepare the adaptor for adjustment to the raised position, that the forward pin by remaining in place enables rapid conversion and immediate firing, that the actual adjusting of the adaptor will not disturb the ammunition belt and that when adjusted it will have a two-point support.

40 I claim:

1. A mount for machine guns embodying a support, a cradle trunnioned on the support and having provision for the rear attachment of a gun, an adaptor arranged for sliding movement on the cradle trunnion and having provision for the forward attachment of the gun, a portion of said adaptor when in lowered position bearing against the cradle forwardly and below the cradle trunnion, means whereby the lower extremity of the adaptor is confined when the adaptor is in raised position, and means for clamping the adaptor in place.

2. A mount for machine guns embodying a support, a cradle trunnioned on the support and having provision for the rear attachment of a gun, an adaptor arranged for sliding movement on the cradle trunnion and having provision for the forward attachment of the gun, means whereby the lower extremity of the adaptor is confined when the adaptor is in raised position and means for clamping the adaptor in place.

3. A mount for machine guns embodying a support, a cradle trunnioned on the

support and having provision for the rear attachment of a gun, an adaptor arranged for sliding movement on the cradle trunnion and having provision for the forward attachment of the gun and means whereby the lower extremity of the adaptor is confined when the adaptor is in raised position.

4. A mount for machine guns embodying a support, a cradle trunnioned on the support and having provision for the rear attachment of a gun, an adaptor arranged for sliding movement on the cradle trunnion and having provision for the forward attachment of the gun and means for clamping the adaptor in place.

5. A mount for machine guns embodying a support, a cradle trunnioned on the support and having provision for the rear attachment of a gun, an adaptor having a sliding connection with the cradle trunnion and bearing on the cradle when in lowered position, a forward gun attaching means carried by the adaptor and bearing on the cradle, means whereby the lower extremity of the adaptor is confined when the adaptor is in raised position and means for clamping the adaptor in place.

6. A mount for machine guns embodying a support, a cradle trunnioned on the support and having provision for the rear attachment of a gun, an adaptor having a sliding connection with the cradle trunnion and bearing on the cradle when in lowered position, a forward gun attaching means carried by the adaptor, means whereby the lower extremity of the adaptor is confined when the adaptor is in raised position and means for clamping the adaptor in place.

7. A mount for machine guns embodying a support, a cradle trunnioned on the support and having provision for the rear attachment of a gun, an adaptor having a sliding connection with the cradle trunnion and bearing on the cradle when in lowered position, a forward gun attaching means carried by the adaptor, and means whereby the lower extremity of the adaptor is confined when the adaptor is in raised position.

8. A mount for machine guns embodying a support, a cradle trunnioned on the support and having provision for the rear attachment of a gun, an adaptor having a sliding connection with the cradle trunnion and bearing on the cradle when in lowered position, a forward gun attaching means carried by the adaptor and means for clamping the adaptor in place.

9. A mount for machine guns, embodying a support, a cradle trunnioned on the support and having provision for the rear attachment of a gun, an adaptor adjustably mounted by the support and having provision for the forward attachment of a gun and means for securing the adaptor in position of adjustment.

10. A mount for machine guns embodying a support, a cradle having a provision for the rear attachment of a gun, a trunnion for mounting the cradle on the support, abutting bushings on the trunnion, an adaptor having provision for the forward attachment of a gun slidably mounted on the trunnion and a clamping handle on the trunnion for securing the adaptor in place. 15
- 5 11. A mount for machine guns embodying a support, a two-part gun carrying cradle on the support, one part mounted for pivoted movement and the other part mounted for sliding movement, independent of the first mentioned part. 15
- 10 12. A mount for machine guns embodying a support, a cradle trunnioned on the support and a member having provision for the forward attachment of a gun and bearing against the cradle forwardly of and below the cradle trunnion. 20
